UNITED STATES PATENT OFFICE.

LAWRENCE P. CRECELIUS, OF CLEVELAND, OHIO, ASSIGNOR TO THE ELECTRIC RAILWAY IMPROVEMENT COMPANY, OF CLEVELAND, OHIO, A CORPORATION OF OHIO.

RAIL-BONDING APPARATUS.

1,242,525.

Specification of Letters Patent.

Patented Oct. 9, 1917.

Application filed October 5, 1914, Serial No. 865,065. Renewed June 24, 1916. Serial No. 105,723.

To all whom it may concern:

Be it known that I, LAWRENCE P. CRECELIUS, a citizen of the United States, residing at Cleveland, in the county of Cuyahoga and State of Ohio, have invented a certain new and useful Improvement in Rail-Bonding Apparatus, of which the following is a full, clear, and exact description.

This invention relates to rail bonding apparatus and is a modification of the rail bonding apparatus forming the subject matter of a prior application filed by Paul H. Eberlein and myself on April 5, 1913, Serial No. 759,074.

15 In said prior application there is disclosed a rail bonding apparatus which is designed to be clamped to the rail so as to be located at the side thereof, and which includes two heating electrodes designed to be simultaneously pressed against the terminal of the rail bond so that current will pass through the two electrodes and through the bond with the three parts in series relationship, the said electrodes being capable of adjustment toward and from the rail simultaneously or individually. The relative adjusting of the electrodes is effected by means of manually-operable screw attachments, which permit the operator to equalize the pressures 25 between the two electrodes and the bond terminal in such a manner that equal or predetermined heating effects are obtained at both electrodes. Said apparatus therefore has the advantages that it does not interfere 30 with a traffic over the rails being bonded, and can be easily moved from point to point, especially as the series relationship of the electrodes during the bonding operation reduces to such an extent the amount of current 35 required for bonding purposes that there may be utilized considerably smaller and more flexible conductors than heretofore to conduct the current between the electrodes and the source of current.

40 The object of the present invention is to provide a bonding apparatus having substantially the advantages of said prior apparatus, but wherein the equalization or adjustment of pressures between the two electrodes and the bond terminal is accomplished in a different manner and by somewhat simpler means.

A further object is to provide certain im-

provements which increase the speed and reduce the cost of bonding a track.

The above and other objects are accomplished by my invention which has for one of its features means whereby there is a self-adjustment of electrodes as the latter are simultaneously pressed against the terminal of the bond. Further important features of my invention reside in the manner of supporting the electrode carrying part of the apparatus on a clamp or holder which is designed to be secured to the rail to be bonded, and in the means by which electric conductors can be quickly attached to or detached from the electrodes.

My invention may be further briefly summarized as consisting in certain novel details of construction and combinations and arrangements of parts which will be described in the specification and set forth in the appended claims.

In the accompanying sheets of drawings showing two forms of my invention, Figure 1 is a plan view of one form of the apparatus applied to a rail, parts being in section; Fig. 2 is a side view of the apparatus with the rail in section; Fig. 3 is a sectional view substantially along the line 3—3 of Fig. 2; Fig. 4 is a plan view similar to Fig. 1 showing a modification; Fig. 5 is a side elevation of the same; and Fig. 6 is a sectional view substantially along the line 6—6 of Fig. 5.

In Figs. 1 to 3 the rail bonding apparatus, which it may be here stated is utilized preferably for brazing copper bonds to steel rails, includes in this instance a rail clamp having two clamping parts, 10 and 11, which in the present embodiment of the invention are adapted to extend beneath the flange of the rail which is shown at 12, and to grip opposite flanges in the manner best shown in Fig. 3. It is not essential, however, that the apparatus be supported as here shown or have a rail gripping or clamping means of the particular form illustrated, as other ways of obtaining the desired result and especially of securing or clamping the apparatus to the rail may be utilized. I may say further at this point that by the term "rail" employed in connection with the rail clamp I mean to include those parts which in effect consti-

2
tute parts of the rail such as the fish plates. The members 10 and 11 are adapted to slide relatively one within the other, and the member 10 carries a rotatable spindle or 5 rod 13 having a suitable hand wheel 13^a and a threaded portion 13^b which engages in a suitable threaded socket of the member 11, so that the gripping jaws on the two component parts 10 and 11 of the clamp 10 may be moved into and out of rail clamping position.

It will be observed that the member 10 of the clamp is provided at its upper surface at one side of the rail with a projection or supporting arm 14 which is at right angles to the clamping spindle 13 or parallel to the rail when the apparatus is in position for bonding and extends beyond both sides of the clamp. Seated on this 15 member 14 is an electrode supporting base member 15 having on its lower surface a slot or groove which receives the member 14, and is somewhat wider than the latter, so that the electrodes and the electrode 20 holding part of the apparatus, may be lifted bodily from the clamp. When the electrodes are pressed against the bond terminal, that is when the apparatus is in use, the front edge portion of the member 14 25 bears against the edge of the slot in the member 15, these portions of the slot and member 15 being undercut, as shown in Fig. 2. The base member 15 carries an electrode carrier or slide 16 which is adapted to be moved toward and from the rail, said carrier or slide having a dovetail projection which fits in a dovetail slot located in the upper portion of the base member 15 and extending at right angles to the rail. 30 For the purpose of adjusting the member 16 relative to the member 15 toward and from the rail, the member 15 is provided with an adjusting shaft or spindle 17 having a suitable hand wheel 17^a and a threaded portion 40 17^b which engages in a suitable threaded socket of the member 16.

This member 16 supports two adjacent box like electrode holders 18 in which are secured two high resistance heating electrodes 19 which are preferably made of carbon, the inner ends of the electrodes being adjacent each other and being adapted to be simultaneously pressed against the bond terminal which is indicated at 20. These 45 electrode holders 18 are secured by insulated bolts indicated at 21 in Fig. 2 to shoes 22, which have a close working fit and are adapted to have slight sliding movement in guideways 23 in the carrier 16. The holders 18 are securely insulated from the shoes, the separating insulation between these parts being shown at 24. Between the shoes 22 and the rear ends of the guideways 23, are coil springs 25 which yieldingly resist rearward movement of the shoes in the guide-

ways of the carrier and cause a self-adjustment or automatic equalization of the pressures of the two electrodes on the bond terminal when the carrier is moved forwardly toward the rail to cause the electrodes to 76 press against the terminal.

The electrode holders are provided with terminal members 26, to which electric conductors for supplying current to the electrodes are adapted to be connected. The 75 terminal members here shown consist of portions of so-called quick detachable couplings. The source of current for the electrodes will usually consist of a transformer which may be located at any point reasonably near the bonding apparatus. The leads or conductors between the transformer and the electrodes may by reason of the series arrangement of the electrodes, as heretofore explained, be sufficiently small, light and 80 flexible that conductors of considerable length may be employed enabling the bonding apparatus to be carried from point to point, so that several bonds may be applied without requiring that the transformer be 85 moved. When the leads are attached to the electrode holders and when the electrodes are brought up against the bond terminal, current will pass from one electrode into the 90 terminal and from the terminal into the other electrode; in other words, in series through the three parts. The terminal will thus be heated by conduction from the heating electrodes, and it will be heated also by the current passing through the bond and by 100 the heat generated at the points of contact between the electrodes and the bond terminal. The heat thus applied to the terminal will pass by conduction to the rail through any suitable brazing or soldering material 105 which will be interposed between the bond terminal and the rail, with the result that the bond terminal will be brazed to the rail very quickly.

Substantially uniform heating effects are 110 obtained opposite both electrodes, because of the provision of the springs 25 which will ordinarily be of equal length and strength, the said springs being compressed when the electrodes are simultaneously brought up to 115 and clamped against the bond terminal, and by their yielding action permitting the electrodes to adjust themselves to any slight inequalities in the bond terminal so that both electrodes will bear against the terminal 120 with equal or substantially equal pressures. This avoids unequal heating effects and the destruction of one part of the bond by excessive heating before the other part is brought to brazing temperature, as would 125 result from pressing against the terminal two relatively rigid or rigidly mounted electrodes not capable of adjustment relative to each other or to the carrier which is moved by the adjusting screw.

The apparatus as above described can be used very successfully with a bond terminal of the T-type, wherein the terminal is symmetrical as regards thermal characteristics on opposite sides of its transverse axis. In the event that the terminal does not have equal thermal characteristics on opposite sides of its transverse axis, as when the connector extends from one end of the terminal 5 rather than from its middle point, the parts of the terminal opposite the two electrodes would not be heated equally and uniformly to brazing temperature because the connector extending from end of the terminal conducts away heat from that end, with the result that the free end would heat up much more quickly. To adapt the apparatus for bonds of the type which are not thermally symmetric the electrodes can be caused to 10 bear unequally against the terminal by the use of springs of unequal stiffness. For the electrode opposite which a greater heating is desired a weaker spring can be employed than is employed with the other electrode, so that the former electrode will be 15 pressed against the terminal with less pressure than the latter, resulting in greater resistance of contact and a generation of more heat at that part of the terminal where the greater heating is desired.

There are numerous advantages in the particular manner previously described of supporting the base member 15 and the parts carried thereby on the supporting arm or 20 projection 14 of the clamp. In the first place, the base member and the electrodes can be adjusted lengthwise of the rail by simply sliding the base member along the member 14 after the clamp is in place, so 25 that the electrodes can be accurately positioned with reference to the bond terminal. Furthermore, the easy removability of the base member from the clamp or attachment of the base member to the clamp admits of 30 the use of several clamps with one set of heating electrodes. I have found that bonding can be facilitated if a number of clamps are employed, thus allowing the clamps to be secured to the rails at or substantially at 35 points where the bonding is to be done, and then the operator who does the bonding has simply to lift the base member with the electrodes from one clamp and carry the same to the next clamp which is already in position.

I have found also that bonding can be 40 carried on very rapidly by utilizing several sets of the bonding apparatus such as herein disclosed, including the clamp and the electrodes. These different sets may be secured 45 to the rails at the desired points, and when the bonding is completed at one point the operator may detach the conductors from the electrodes and attach them to the electrodes of the next bonding set. The speed 50 at which this can be done is due in large

part to the quick detachable couplings or electric connections previously described, and for this and other reasons the couplings or connectors of the quick detachable type have great importance in this apparatus. 70

In the modification shown in Figs. 4 to 6, substantially the same results are obtained in a somewhat different manner than with the apparatus shown in Figs. 1 to 3. In Figs. 4 to 6 the rail clamp composed of the 75 parts 10, 11, 13 and 14 and the member 15 are the same as the corresponding parts in the first described construction, and hence the previous description and reference characters as to such parts will apply to Figs. 80 4 to 6. This member 15 carries a slide or electrode carrier 30 corresponding to the slide 16 of the first described construction, this slide having a dovetail sliding connection with the member 15, such that it may be 85 moved toward and from the rail, the adjustment being accomplished as in the first case by an adjusting rod or spindle 30a.

The slide 30 carries two high resistance heating electrodes 31 which are similar to 90 and are disposed relative to each other, the same as in the first described construction. These electrodes are mounted in holders 32 which are rigidly bolted to and insulated from a plate 33, the rear end of which is 95 movably connected by a swivel pin 34 to the rear portion of the slide 30. This construction differs from the first in the respect that the electrodes are rigidly held or are rigid with respect to each other, but are both 100 slightly movable with respect to the slide or carrier 30. When the slide is moved inwardly and the electrodes are forced against the terminal of the bond, the electrodes will, to an extent, adjust themselves to inequalities on the face of the bond terminal somewhat as with the construction first described. The second construction is, however, less effective in this respect than the first, but may be employed with success with certain 110 types of bonds which are thermally symmetric on opposite sides of the transverse axis, especially if a spelter or braze of low fusion point is employed.

Having thus described my invention, what 115 I claim is:—

1. In an apparatus for uniting metal bodies, a support, a pair of adjacent high resistance heating electrodes carried by said support and insulated from each other so 120 that they may be connected in a series circuit, means for simultaneously moving said electrodes toward and from the bodies to be united, said electrodes being movably mounted in such a manner that when they 125 are pressed against one of said bodies to be united the relative pressures of the two electrodes on said body are automatically adjusted.

2. In combination in an apparatus for 130

- uniting metal bodies, a support, a pair of adjacent high resistance electrodes carried by said support and insulated from each other so that they may be connected in a series circuit, means for simultaneously moving said electrodes toward and from said bodies and for causing the same to bear forcibly against one of the bodies, and means whereby when said electrodes are pressed against one of said bodies the individual pressures of the two electrodes are automatically adjusted.
3. In an apparatus for uniting metal bodies, a support, a pair of high resistance electrodes carried thereby and insulated from each other so that they may be connected in a series circuit, said electrodes having their inner ends adjacent each other, means for moving said electrodes toward or from said bodies and for causing the ends of said electrodes to bear forcibly against one of said bodies, and means whereby said electrodes are automatically caused to bear with predetermined relative pressures against said body.
4. In combination in an apparatus for uniting metal bodies, a support, a pair of adjacent high resistance electrodes carried by said support, and insulated from each other so that they may be connected in a series circuit, adjusting mechanism by which said electrodes may be simultaneously shifted and caused to bear against one of said bodies, said electrodes being mounted in such a manner that the relative pressures of the two electrodes are equalized when pressure is applied through said adjusting mechanism.
5. In a rail bonding apparatus, a support adapted to be held in a fixed position with reference to a rail and at one side of the same, an electrode carrier carried by said support, adjusting means by which said carrier may be moved toward and from the rail, a pair of high resistance electrodes mounted on said carrier, and insulated from each other so that they may be connected in a series circuit; the mounting of said electrodes on said carrier permitting an automatic pressure adjustment of the two electrodes on the bond terminal when pressure is applied through said adjusting means.
6. A rail bonding apparatus, a support, rail clamping means holding the same at one side of the rail, a pair of high resistance electrodes carried by said support and insulated from each other so that they may be connected in a series circuit, an adjusting device by which said electrodes may be simultaneously moved toward or from the rail and may be caused to bear forcibly against a terminal of a bond to be united to the rail, said electrodes having a mounting which permits self-adjustment of the pressures of the two electrodes on the bond.
7. In a rail bonding apparatus, a support, means by which said support may be clamped to the rail at one side of the latter, an electrode carrier supported by said support for movement toward and from the rail, an adjusting device for simultaneously moving the electrodes toward and from the rail and for simultaneously causing both electrodes to bear forcibly against a terminal of the bond to be united to the rail, said electrodes having a loose mounting on said carrier so that they will bear against the terminal with predetermined pressures when pressure is applied through said adjusting mechanism.
8. In a rail bonding apparatus, a support, clamping means by which said support may be rigidly supported from and at the side of the rail, an electrode carrier having a sliding connection with said support for movement toward and from the rail, a pair of insulated electrodes supported by said carrier, and having their inner ends adjacent each other, an adjusting device by which said carrier may be moved toward and from the rail, and by which the inner ends of the electrodes will be caused to bear forcibly against the terminal of a bond to be united to the rail, said electrodes being mounted loosely on the carrier so that they will automatically be caused to bear against the terminal with predetermined relative pressures when pressure is applied through said adjusting device.
9. In a rail bonding apparatus, a rail clamp, a support mounted thereon, an electrode carrier carried by said support and movable toward and from the rail, one or more electrodes supported by said carrier, means for shifting said carrier and for causing the electrode or electrodes to bear against a terminal of the bond to be united to the rail, said support and the parts carried thereby normally resting on said clamp, said support and clamp having engaging parts which enable the support to be held in fixed position relative to the clamp when pressure is applied on to the bond, and which enable the support and the parts carried thereby to be lifted as a unit from the clamp.
10. In a rail bonding apparatus, a rail clamp having a part projecting laterally to one side of the rail, a support for the bonding electrodes resting on said laterally projecting part of the clamp, one or more heating electrodes carried by said support, means by which said electrode or electrodes may be moved toward and from the rail, said support normally resting on the clamp, and one having a projection, and the other a slot which receives the projection, said slot and projection permitting the support to be held rigidly to the clamp when pressure is applied to the bond terminal, and permit-

- ting the support and all the parts carried thereby to be lifted from the clamp.
11. In a rail bonding apparatus, a rail clamp having a part projecting laterally to one side of the rail when the clamp is secured to the rail, a projection on said laterally projecting part of the clamp, a support for one or more heating electrodes having a slot on its lower side wider than said projection and loosely receiving the latter, so that the support may be lifted bodily from the clamp, one or more heating electrodes carried by the support, and means by which said electrode or electrodes may be adjusted toward and from the rail.
12. In a rail bonding apparatus, a rail clamp having a part projecting laterally to one side of the rail when the clamp is secured to the rail, a member carried by said laterally projecting part of the clamp, and extending transversely of said clamp or lengthwise of the rail, a support for one or more heating electrodes, having a slot extending lengthwise of the rail, said slot loosely receiving said member, a slide on the upper side of the support and movable toward and from the rail in a direction at right angles to said slot, means for adjusting said slide, and one or more heating electrodes carried by said slide.
13. In a rail bonding apparatus, a rail clamp having a part projecting laterally to one side of the rail when the clamp is secured to the rail, an electrode support, said laterally projecting portion of the clamp and said support having engaging parts which enable the support to be moved relative to the clamp lengthwise of the rail, one or more heating electrodes carried by the support, and means for moving said electrode or electrodes toward and from the rail.
14. In a rail bonding apparatus, a rail clamp having a part projecting laterally to one side of the rail when the clamp is in clamping engagement with the rail, a support for one or more heating electrodes mounted on the laterally projecting portion of the clamp, said portion of the clamp and support having engaging portions including a slot in one part and a member on the other part and engaging said slot, said slot and member extending parallel to the rail and permitting the support to be adjusted lengthwise of the rail, one or more heating electrodes carried by the support, and means for moving the same toward and from the rail.
15. In a rail bonding apparatus, a rail clamp having a support which, when the clamp is secured to a rail, is at one side of the rail and extends longitudinally thereof, and a bonding structure supported on said support and movable along the same lengthwise of the rail.
16. In a rail bonding apparatus, a rail clamp having a support at one side of the rail when the clamp is in engagement with the rail, and a rail bonding structure removably seated on said support and including one or more electrodes, together with means for clamping the same against a bond.
17. In a rail bonding apparatus, a rail clamp having a support which is at one side of the rail when the clamp is secured to the rail and a rail bonding structure removably seated on said support and having on the lower side thereof a slot which receives the top of the said support.
18. In a rail bonding apparatus, a rail clamp having a part extending laterally to one side of the rail when the clamp is in operative position leaving the gage line clear and unobstructed, and bonding means including an electrode supported on said laterally extending part of the clamp in such a manner that it may be lifted as a unit from the clamp and means whereby the electrode may be pressed against the bond with sufficient pressure for bonding purposes.
19. In a rail bonding apparatus, a rail clamp having an electrode supporting part at one side of the rail when the clamp is in operative position leaving the gage line clear and unobstructed, and bonding means including a carrier for one or more electrodes connected to said supporting part of the clamp in such a manner that the bonding means may press the bond firmly against the rail and with sufficient pressure for bonding purposes or may be removed as a unit from the clamp.
20. In a rail bonding apparatus, a rail clamp having an electrode supporting part located at one side of the rail when the clamp is in operative position, said part extending longitudinally of the rail, and bonding means including an electrode supported on said part of the clamp and movable lengthwise thereof parallel to the rail.
21. In a rail bonding apparatus, a rail clamp having an electrode supporting part located at one side of the rail when the clamp is in operative position and bonding means adapted to engage and heat a bond supported on said part of the clamp in such a manner that it may be moved lengthwise of the rail within certain limits or may be bodily removed from the clamp.
- In testimony whereof, I hereunto affix my signature in the presence of two witnesses.
